UNITED STATES PATENT OFFICE.

FRED A. NEIDER, OF AUGUSTA, KENTUCKY.

BUCKLE AND LOOP.

SPECIFICATION forming part of Letters Patent No. 309,156, dated December 9, 1884.

Application filed October 13, 1884. (No model.)

To all whom it may concern:

Be it known that I, FRED A. NEIDER, a citizen of the United States, and a resident of Augusta, in the county of Bracken and State 5 of Kentucky, have invented a certain new and useful Improvement in Buckle and Loop, of which the following is a specification.

The object of my invention is a combined buckle and loop that can be cheaply produced 10 and quickly secured to the back-stay or curtain of the carriage, for which purpose it is especially designed. It is an improvement upon the buckle and loop for which Letters Patent were granted to me June 10, 1884, 15 No. 300,111.

In the form of buckle clip or strap shown in my said patent the points by which the buckle, strap, and loop were secured to the curtain or back-stay were struck up from the same piece 20 of metal which formed the clip. As the clip is made of thin sheet metal these fastening-points had to be made of considerable width in order to prevent their straightening out when a strain was brought upon the buckle, and also 25 to give sufficient body to the male die to prevent its breaking when punching several thicknesses of metal. I overcome these objections by omitting the tongues or fastening-clips from my present buckle-clip blank, which effects a 30 great saving of metal, as well as requiring less expensive dies, and I use in place of the fastening-tongues, which required slits to be first made in the leather for attaching my former loop, the common pointed clinching-tack or 35 clout-nail, which I first pass through a perforation in one end of the blank. The nail is held in place by the opposite end of the blank when bent over after the buckle is inserted.

In the accompanying drawings, in which 40 similar parts are indicated by similar reference-letters wherever they occur, Figure 1 is a central longitudinal section of a buckle and loop embodying my invention, shown attached to the curtain or back-stay of a carriage. Fig. 45 2 is a vertical transverse section of the same, taken through the line $\alpha\alpha$ of Fig. 1, showing the tack before the point is clinched down. Fig. 3 is a perspective view of the buckle and clip detached from the loop. Fig. 4 is the 50 stamped-out blank from which the buckle-clip is formed. Fig. 5 is an inverted plan view of

an open-ended buckle-loop provided with my improvements. Fig. 6 is a plan view of a clip-blank adapted to receive a buckle at each end.

The box-loop A is of the usual form, and may 55 be made of thin sheet metal, leather, or other suitable material, stamped or formed to the proper shape. The metal clip B is stamped out to the form shown in Fig. 4 if a single buckle is to be attached to it, or to the form 60 shown in Fig. 6 if it is to receive two buckles. After it is stamped out the wings b are turned up at a right angle to the central part in suitable forming-dies. The tack C is now inserted 65 through the perforation near the end of the partially-formed blank, the point projecting 70 up in the same direction as the wings b, and the tongue of buckle D passed through the slot e. The blank is then doubled over, as shown clearly in Fig. 3, the tack-head coming 75 between the folds securing it firmly in place. One of these clips with the buckle attached is inserted in each end of the box-loop A, thus completing the buckle and loop shown in Figs. 1, 2, and 5.

The blank, Fig. 6, is formed up and the 75 buckles and tacks secured in place in the same manner as above described; but the clip and buckles are secured to the loop permanently as follows: Before the loop A is completely 80 formed—that is, when its sides are bent at right angles to the top, forming a three-sided box—the clip and its buckles are inserted with the edges of the wings b resting upon the inside of the loop-top. The edges of the loop are 85 then bent down upon the bottom of the clip, confining it in place, and forming a square tube with a buckle at each end.

To secure my buckle and loop in place, the tacks are forced through the goods E of the 90 curtain or back-stay and clinched down upon the opposite side; the point of the tack, turning as it is hammered over, enters the goods, and makes a very secure fastening. The wings b, resting against the top of the loop, 95 will sustain the metal of the clip while it is being clinched.

It will be seen that in applying my buckle and loop it is not necessary to first measure the places where the slits are to be made, as 100 when the flat clinches are used. It is only necessary to place the device in the proper posi-

tion and force the points through, and as the points return into or through the goods they are not liable to straighten out by any strain applied to the buckle. I have also shown 5 in the drawings a thin metal plate, F, on the inside of the goods E, through which the tacks pass before being clinched down. This adds to the strength, but is not absolutely essential, as my clinching-points make a very 10 secure fastening without it.

What I claim as new, and desire to secure by Letters Patent herein, is—

1. The clip for holding the buckle folded, as described, and provided with the tacks C, passing through the lower fold of the clip, and hav- 15

ing the opposite fold turned down upon the head of the tack, to confine it in place and hold it while being clinched over to secure it in place.

2. The combination, substantially as specified, of the buckle-loop A with the buckle D and attaching-clip B, provided with tacks C, held in place between the folds of the clip, and the wings b, to hold the parts together and furnish a support for the tacks while being 20 clinched.

FRED A. NEIDER.
